UNITED STATES PATENT OFFICE.

ZENAS P. CANDEE, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

FEED MECHANISM.

Application filed March 8, 1920. Serial No. 364,293.

To all whom it may concern:

Be it known that I, ZENAS P. CANDEE, a citizen of the United States, residing at Waterbury, in the county of New Haven and State of Connecticut, have invented certain new and useful Improvements in Feed Mechanisms, of which the following is a specification, reference being had therein to the accompanying drawings.

- 10 This invention relates to new and useful improvements in feed mechanisms and has for its object, among other things, to provide a duplex feeding device for delivery of a plurality of articles, each at a different 15 station from a single dial device that receives the different articles in separate groups; and further to design the parts that the elements may be of simple design and easy of assembly.
- 20 To these and other ends, my invention consists in the feed mechanism, having certain details of construction and combinations of parts, as will be hereinafter described and more particularly pointed out 25 in the claims.

Referring to the drawings, in which like numerals of reference, designate like parts in the several figures;

Figure 1 is a plan view of my improved 30 mechanism;

Figure 2 is a transverse sectional view thereof, taken upon line 2—2 of Figure 1;

Figure 3 is an enlarged detail plan of a portion of the mechanism; and

35 Figure 4 is an enlarged sectional view in detail, taken upon line 4—4 of Figure 3.

As herein shown and described the feed mechanism is designed to deliver at two different stations the cap of a collapsible tube 40 or similar device and disks that are inserted therein, the latter usually being made of cork or other similar material, but, of course, the invention is not limited to such use.

The caps above referred to are relatively 45 of substantial size and weight as compared with the disks which are small, light in weight and somewhat difficult to control automatically.

With my improved mechanism I provide 50 a dial upon which are placed the caps and upon the same dial in an enclosed space are also placed the disks, and guiding devices are provided for receiving and guiding

singly in succession the caps and disks so that they are delivered to predetermined 55 stations, the rotation of the dial providing the means for conducting these articles through each of the guiding means. From these delivery stations mechanisms are provided for assembling the disks and caps, 60 which may be of any preferred type within the spirit of this invention, but is not shown herein, as not being essential to the understanding of the improved device.

Referring now to the drawings, the numeral 10 designates the bed of the machine in which is fixed a stud 11, upon which is rotatably mounted a beveled gear 12, into which mesh the teeth of a pinion 13 mounted upon a shaft 14 rotatable in a journal box 70 15 secured to the said bed, a three-step grooved cone pulley 16 fixed on the shaft 14 providing means whereby power is imparted to the shaft 14 and through the pinion 13 to the gear 12.

An apron 17 fixed to the bed 10 and projecting laterally therefrom provides a convenient receptacle for a preliminary assembly and arrangement of the caps. This apron can be of any size or shape and is 80 available for any convenient purpose in connection with the use of the apparatus.

Fixed to the gear 12 is the dial 18, the top surface of which is preferably in the same plane as the top of the apron 17, the 85 latter being concaved at one edge to receive the same, as shown in Figure 1.

Secured to the bed 10 by the bolts 19 is a bracket 20, and fixed therein is a stud 21, upon which is mounted the drum 22, which 90 is rotated from a pinion 23 fixed to the gear 12, the teeth of which mesh into the teeth 24 around the periphery of the said drum. This drum is provided at its upper end with the outwardly flaring flange 25. It is arranged so that the lower edge thereof may be set at varying distances from the top of the dial 18, and held in such position by the set screw 52. The guide plates 26 and 27 have curved faces thereon of substantially 100 the same arc as that of the outside of the lower portion of said drum. These guide plates rest upon the top of the dial 18 and are supported with an open space 28 therebetween the guide strip 27 being supported 105 by the block 29 which is secured thereto

and adjustable within the slot 30 in the bracket 20, being held in its adjustable positions by the nut 31. The guide strip 26 is supported by the block 32, which is adjustable within the slot 33 on the bracket 20 and secured in its adjustable positions by the screw 34.

The disk guide-way consists of the parallel guide plates 35 and 36, the former being connected with the block 29 and the latter with the block 32, and the relative width of the open space therebetween being determined by the adjustment of the said blocks in relation to the bracket 20, the former, it being remembered, being adjustable in the slot 30 and the latter in the slot 33.

The outer ends of the guide plates 35 and 36 are supported by the arm 40 fixed to the bracket 20 and curved at 37 so as to deliver the articles to a predetermined station, which position may be varied relatively according to the direction of inclination of the plates 35 and 36 and the curvature at the end thereof.

25 The articles in this case, the disks, that pass through between the plates 35 and 36 are prevented from piling one on top of the other by a cover plate 38, which is connected with guide plate 35 by screws 53 that project through slots in said guide plate thereby permitting relative adjustment of said cover plate. The guide plate 35 and cover plate 38 are separated by the blocks 39. When in position the underside of the cover plate 38 is above the top of the dial 18 a sufficient distance to just permit the disks to pass thereunder, while lying flat.

40 The wall 41 of the bed 10 projects upwardly above the dial 18 and forms one side of a guideway 42, the other side being formed by a guide strip 43 that is supported at one end by a block 44 adjustably secured to the bed 10 by the bolt 45 that passes through the slot 46, the other end being bowed at 47 and secured to the holder 48 attached by the bolt 49 to the bracket 20.

45 In operation the dial 18 and drum 22 rotate in opposite directions and the caps are placed on the dial outside of the bowed portion 47 of the guide strip 43 and by the rotation of the dial they are carried into the guideway 42 and are discharged therefrom at the opposite end of said guideway, at a delivery station from which they are conducted by other mechanisms, the construction and operation of which is not material to this invention. The disks are thrown indiscriminately into the drum 22 and these also rest upon the top of the dial 18; the pins 50 which are supported loosely in the arms 51 of the drum 22 break up any crowding or bunching of these disks and provide an agitator therefor. These pins, however, are not necessary, but facilitate 60 the feeding action. As the disks are moved

around against the curved face of the guide plate 26 they pass into the opening 28, one by one and travel in the guideway between the plates 35 and 36 underneath the cover plate 38 and are delivered to a station near 70 the outer edge of the said dial, being conducted therefrom by mechanisms not essential to this invention and not therefore shown or described herein.

75 The movement of the dial 18 in an anti-clockwise direction and the drum in a clockwise direction results in the carrying around on the dial to the other side of the drum any jam or crowding of the disks, thus providing means whereby the improper jamming 80 is prevented.

There are minor changes and alterations that can be made within my invention, aside from those herein suggested, and I would therefore have it understood that I do not 85 limit myself to the exact construction herein shown and described, but claim all that falls fairly within the spirit and scope of the appended claims.

Having described my invention, what I 90 claim as new and desire to secure by Letters Patent, is:

1. The combination in a feed mechanism; of a rotary dial; a rotary drum; means for rotating the latter in a direction the reverse 95 of said dial; and means for conducting articles from said drum and said dial to different delivery stations.

2. The combination with a feed mechanism; of a rotary dial; a rotary drum mounted upon one side of the center of said dial, with the latter forming a bottom therefor; means for rotating the drum in a direction opposite to the dial; and guide means for conducting articles over the top of said dial 105 one of said means leading from said drum.

3. The combination in a feed mechanism; of a rotary dial; a rotary drum; means for rotating the latter in a direction the reverse of said dial, means connected with 110 said drum for agitating the articles therein; and means for conducting articles from said drum and said dial to different delivery stations.

4. The combination with a feed mechanism; of a rotary dial; a rotary drum mounted upon one side of the center of said dial, with the latter forming a bottom therefor; means for rotating the drum in a direction opposite to the dial; guide means for conducting articles over the top of said dial; one of said means leading from said drum; and another of said guide means being so arranged as to prevent the articles on the dial outside the drum from being brought into 120 contact therewith.

5. The combination in a feed mechanism; of a rotary dial; a fixed bracket; a drum rotatably connected therewith and so related to 125 said dial that the latter forms a bottom 130

therefor; and toothed means for rotating said drum independently of said dial.

6. The combination in a feed mechanism: of a rotary dial; a member about which said dial rotates; a bracket supported in part by said member; a drum rotatably connected with said bracket and so related to said dial that the latter forms a bottom therefor; and guide means over said dial for conducting articles to delivery stations, one of said guide means being connected with said bracket.

7. The combination in a feed mechanism; of a rotary dial; a member about which said dial rotates; a bracket connected with said member; a drum rotatably connected with said bracket and so related to said dial that the latter forms a bottom therefor; guide means over said dial for conducting articles to delivery stations, one of said guide means being connected with said bracket and means for adjusting the relative positions of the parts of the guide means connected with the bracket toward each other.

8. The combination in a feed mechanism; of a rotary dial; a fixed bracket; a drum rotatably connected therewith and so related to said dial that the latter forms a bottom therefor; and means for rotating said drum independently of said dial.

9. A feed mechanism for feeding articles of different structure, comprising a rotary dial, a circular member above the friction face of said dial which divides the surface of said dial into different parts whereby articles of different character may be separated from each other and one of the groups of articles entirely surrounded by said circular member, except where discharged therefrom, and a guideway leading from each of the separated parts of said rotary dial whereby the articles upon the face of said dial are automatically and separately deliv-

ered by said dial to separate and independent delivery stations.

10. A feed mechanism for articles of different character, comprising a rotary dial upon which all of the articles are placed and by which they are moved to delivery stations, articles of like character to one station and other articles of like character but different than the articles delivered to the first station, to another station, means above the dial that entirely surrounds and confines all articles of one character to a definite portion of said rotary dial before moved thereby, and a separate guideway for each of the different kinds of articles extending over said rotary dial and leading to a delivery station, to conduct articles thereto.

11. A feed mechanism for feeding articles of different structure, comprising a rotary dial upon which all of the articles are placed and by which they are moved to delivery stations, articles of like structure to one station and other articles of like structure but different than the articles delivered to the first station, to another station, of a receptacle over the said rotary dial for containing all the articles of one structure and confining them to a definite portion of said rotary dial before moved thereby, a barrier over said dial and adjacent to said receptacle to prevent the movement of said articles from said receptacle by said dial, a guideway leading from said barrier and extending over said rotary dial to conduct the article from said receptacle to a delivery station, and a guideway extending across said rotary dial on the outside of said receptacle for conducting the articles outside of said receptacle to a delivery station.

In testimony whereof, I have hereunto affixed my signature.

ZENAS P. CANDEE.
